UNITED STATES PATENT OFFICE.

GOTTLIEB L. E. KLINGBEIL, OF OMAHA, NEBRASKA.

CHILD'S EDUCATIONAL AND AMUSEMENT DEVICE.

1,378,874.

Specification of Letters Patent. Patented May 24, 1921.

Application filed January 28, 1921. Serial No. 440,749.

To all whom it may concern:

Be it known that I, GOTTLIEB L. E. KLINGBEIL, a citizen of the United States of America, residing at Omaha, in the county 5 of Douglas and State of Nebraska, have invented certain new and useful Improvements in Children's Educational and Amusement Devices, of which the following is a specification.

10 The present invention relates to an educational and amusement device for small children and its object is to provide an apparatus adapted for use in the kindergarten, in primary schools and in the home, constructed in such manner that the interest of 15 the child will be stimulated with a resultant rapid advance in spelling, primary arithmetic and the like.

Further objects and advantages of the invention will be set forth in the detailed description which follows.

In the accompanying drawings:

Figure 1 is a front elevation of an apparatus constructed in accordance with the 25 invention with the parts in position ready for use;

Fig. 2 is a transverse vertical sectional view through the device but with protecting shields, hereinafter described, in position 30 both in front of and behind the keys;

Fig. 3 is a partial longitudinal sectional view through several of the letter tubes;

Fig. 4 is a fragmentary front view illustrating the shield in position over the keys;

Fig. 5 is a fragmentary rear view illustrating the shield over the rear of the keys;

Fig. 6 is a plan view of a tray hereinafter described;

Fig. 7 is an edge elevation of said tray; 40 and

Fig. 8 is an end elevation of the tray.

Like numerals designate corresponding parts in all of the figures of the drawings.

The device comprises a body portion 5 that is supported upon end posts 6 which terminate in legs 7. The body portion 5 is vertically channeled to provide a plurality of letter tubes 8, which receive small flat blocks 9 having the letters of the alphabet 45 thereon. There are enough of the tubes 8 to accommodate all of the letters of the alphabet and numerals from 1 to 9 and, if desired, a cipher, as well as the following signs +, =, ÷, —. The top of the body 5 is inclined or beveled as indicated at 10

which not only facilitates the ready entry of the blocks 9 into the tubes 8 but provides a surface 11 upon which letters of the alphabet, numerals and signs corresponding to the several letter tubes may be placed. A hinged 60 cover 12 is adapted to be folded down between upwardly projecting portions 13 of the end members 5^a of the body 5 and to cover the upper ends of the letter tubes 8. Thus when the device is being carried from 65 place to place, the blocks 9 can not be spilled out of the upper ends of the tubes 8. This is, of course, a matter of advantage in a device intended for use by small children, because they are likely, at any time to turn 70 the apparatus upon its side or upside down.

Disposed beneath the body 5 and supported between the end posts 6 is a letter tray 14. The rear wall of this tray is extended upwardly as at 15 and is secured to 75 a rod 16 the ends of which are engaged with projecting portions 17 of the posts 6. The end walls of the letter tray are fastened to the posts 6 at 18. The letter blocks 9 are to be ejected from the letter tubes 8 by keys 19 80 or 20 as the case may be, and when so ejected the blocks fall into the letter tray 14 and are picked out of this tray, one at a time, by the child and deposited in the channels 21 of an assembly tray 22, shown in Fig. 6. 85

In order to provide sufficient space between the keys 19 and 20 so that any individual key may be selected and pushed without actuating any of the other keys, these keys have been arranged in two rows and in 90 staggered relation with respect to each other. Each tube 8 has a key devoted thereto and the head of the key is lettered or numbered as indicated at 23 with a letter corresponding to the letters borne by the blocks that 95 are deposited in that particular tube. To prevent the accidental actuation of the keys and the accidental discharge of blocks 9 from the tubes 8, a plate or shield 24 is disposed rearwardly of the line of keys and is 100 held in position at one end by hooks 25 (see Fig. 2) and at the other end by a pivoted bar 26, said bar being pivoted at 27 to the plate 24 and having its ends engageable beneath oppositely projecting hooks 28 and 29 105 which are substantially like the hooks 25 except that their free ends extend longitudinally of the body 5 instead of vertically.

A shield or cover 30 of L shape in cross section is adapted to cover the front of the 110

keys. In placing this shield in position it is slipped longitudinally inside of the free ends 31 and 32 of hooks 33 and 34 (see Fig. 2) and engages at the opposite end beneath 5 correspondingly shaped and numbered portions of a pair of hooks. The endwise movement is limited by a stop hook 35. As long as the shields 24 and 30 are in position, the keys 19 and 20 are held against endwise 10 movement. When the device is to be used, these shields are removed after which the keys may be actuated to eject the letters in the following manner. If it be desired to select the letter C, the child will pull out 15 upon the key marked 20^x in Fig. 1. It will be observed that this key bears upon its end the letter C and it is the key that is associated with the letter tube having the C blocks therein. When this key is pulled outwardly 20 until its downwardly projecting portion 20^a abuts against the flange 20^b of the bottom 8^a of the letter tube, one of the blocks C will fall in front of the end 20^c of the key. Then the key is pushed inwardly and the 25 block is ejected through the rear of the body 5 and falls into the letter tray 14. The block is then picked out of the letter tray and placed in one of the channels 21 of the assembly tray 22, as hereinbefore stated, and 30 this operation is repeated to select whatever letters may be necessary to build the word or sentence selected. The bottoms of those letter tubes which receive the lower row 20 of keys is formed by the plate 8^a. The bottoms 35 of the letter tubes which receive the upper row of keys 19 are formed by filling blocks 8^b.

The assembly tray shown in Figs. 6, 7 and 8 is preferably provided with cleats 36 40 across its bottom which cleats not only prevent warping of the tray but render it possible to readily tip the tray so that all of the blocks contained therein may be dumped into the hand when it is desired to return 45 them to the letter tubes 8.

It will be observed that the device of the present invention provides a simple and compact structure, occupying but little space and capable of a wide range of usefulness 50 in the instruction of young children. Its use will appeal to the child more than the mere assembly of the ordinary alphabet blocks would do for the reason that the average child quickly tires of merely assembling 55 blocks. The desire to operate a mechanical apparatus, to see the letter blocks fall therefrom, etc., awakens the interest of the child and incites it to persist in the use of the apparatus.

60 Furthermore the necessity for selectively distributing the letter blocks among the letter tubes, affords a further exercise of the child's mind and further familiarizes the child with the appearance and identity of 65 the respective letters, numbers, signs, etc.

It is to be understood that the invention is not limited to the particular arrangement herein shown and described for it is manifest that the principles involved may be embodied in apparatus of other shapes, proportions and sizes without departure from the invention. 70

Having described my invention, what I claim is:

1. A device of the character described comprising a body portion having a plurality of vertically disposed tubes formed therethrough, letter blocks adapted to fit in and be guided by said tubes, said tubes being correspondingly designated by letters of the alphabet, keys adapted to eject the letter blocks from the bottoms of said tubes, said keys being likewise correspondingly designated by letters of the alphabet, a pair of shields and means for securing the same inwardly and outwardly of said keys to thereby prevent movement of said keys. 75

2. A device of the character described comprising a body portion vertically channeled to provide a plurality of letter tubes the upper edge of said body portion lying at such angle as to render the same visible when looking from the front of the body portion and bearing suitable indicia for the several letter tubes, letter blocks adapted to fit in and be guided by said tubes and a plurality of correspondingly designated keys for ejecting the several letter blocks from the bottoms of said tubes. 90

3. A structure as recited in claim 2 wherein said ejecting keys are disposed in a plurality of rows and the keys of the rows are staggered with respect to each other. 95

4. A structure as recited in claim 2 in combination with a hinged cover adapted to be closed down over the open upper ends of the letter tubes. 105

5. A structure as recited in claim 2 in combination with shields and means for securing the same inwardly and outwardly of said shields to thereby prevent movement of said shields. 110

6. A device of the character described comprising a body portion vertically channeled to form a letter tube, a bottom for said tube and a stop flange carried by said bottom, and a key laterally traversing the bottom of said tube and cut away at its under side for the reception of said stop flange, said key being movable by its outward movement to a position to permit a letter block to fall in the rear thereof and being movable inwardly to eject said block through the rear wall of the body portion. 115

In testimony whereof I affix my signature 120 in the presence of two witnesses.

GOTTLIEB L. E. KLINGBEIL.
